UNITED STATES PATENT OFFICE

HOMER E. GLEASON, OF SEATTLE, WASHINGTON, ASSIGNOR TO CASCADE FIXTURE COMPANY, OF SEATTLE, WASHINGTON, A CORPORATION OF WASHINGTON

DESIGN FOR A CHANDELIER OR SIMILAR ARTICLE

Application filed August 27, 1929. Serial No. 32,556. Term of patent 7 years.

To all whom it may concern:

Be it known that I, HOMER E. GLEASON, a citizen of the United States, residing at Seattle, in the county of King and State of Washington, have invented a new, original, and ornamental Design for a Chandelier or Similar Article, of which the following is a specification, reference being had to the accompanying drawing, forming part thereof.

The figure is a front elevation of a chandelier or similar article, showing my new design.

I claim:

The ornamental design for a chandelier or similar article, as shown.

HOMER E. GLEASON.
